UNITED STATES PATENT OFFICE.

LEO CARBERGER, OF MODLING, AUSTRIA.

ELASTIC RIM.

Application filed September 5, 1922. Serial No. 586,251.

To all whom it may concern:

Be it known that I, LEO CARBERGER, mechanical engineer, a citizen of the Republic of Austria, residing at Modling, in the Republic of Austria, have invented certain new and useful Improvements in Elastic Rims, of which the following is a specification.

This invention relates to elastic rims for carriage-wheels and substantially consists of a hollow cushion or buffer of elastic material and a polygonal frame enclosing the same and capable of being flattened or expanded within the plane of the wheel. 10 When pressure is exerted on the polygonal frame the angles between the sides of the polygons are altered and the pressure is transmitted to the hollow buffers which are deformed in such a way, that the transmission of the pressure unto the hollow buffer is effected from the point of pressure and the opposite point of the polygonal frame with decreasing power on both sides. 20

In the accompanying drawing Fig. 1 diagrammatically shows a partial side view of an elastic rim according to the invention. Fig. 2 shows a partial side view of a modification of the construction shown in Fig. 1. Fig. 3 is a section on the line A—B of Fig. 2 and Fig. 4 shows a polygonal frame in plan view.

On the periphery of the rim *a*, perforated rubber cylinders *b* are arranged at intervals and each is enclosed by a polygonal frame capable of being flattened or expanded in the plane of the wheel. The said frame consists of hinge-bands *d* mounted on bolts *c*. The whole series of polygonal frames are enclosed by a second rim *e* concentrically arranged to the first and are connected with said rims *e* and *a* by means of two of the bolts *c*, which are inserted into the edge flanges *e'* and *a'* of the rims. Lugs *d'* projecting from the polygonal frame prevent longitudinal sliding of the rubber cylinder *b* within the frame. 40

When the wheel is under load the polygonal frame with inserted buffer which is at the lowest point of the wheel is compressed vertically, while the polygonal frame just opposite is stretched. On the intermediate frames a gradually increasing vertical compression and gradually increasing stretching action will take place in accordance

with their relative position with respect to 55 the vertical.

The pressure is transmitted to the hollow rubber cylinders and effects a corresponding alteration of form of them. 60

What I claim is:

1. A wheel of the character described comprising an inner rim, an outer rim, a plurality of independent spacing devices interposed between the rims and spaced apart, each device comprising an endless series of 65 articulated links, and yielding cylindrical expansion members surrounded by said links.

2. A wheel of the character described comprising an inner rim, an outer rim, a plurality of spacing devices independent of one another interposed between the rims and spaced apart, each device comprising a series 70 of plates, pins pivotally connecting said plates together, pins connecting some of the plates to the rims, and yielding cylindrical buffers having a central perforation surrounded by the plates. 75

3. A wheel of the character described, comprising an inner rim, an outer rim, a plurality of spacing devices interposed between the rims and spaced apart, each device comprising a series of plates, pins pivotally connecting said plates together, pins connecting some of the plates to the rims, yielding cylindrical buffers surrounded by the plates, and means to prevent axial movement of the buffers. 85

4. A wheel of the character described, comprising an inner rim having outwardly extending lateral flanges, an outer rim having inwardly extending lateral flanges, spacing devices interposed between the rims and flanges, each device comprising an endless series of pivotally connected plates pivotally connected to the side flanges, and a yielding cylindrical buffer mounted within each series of plates. 95

5. A wheel of the character described, comprising an inner rim having outwardly extending lateral flanges, an outer rim having inwardly extending lateral flanges, spacing devices interposed between the rims and flanges, each device comprising an endless series of pivotally connected plates pivotally connected to the side flanges, a yielding cylindrical buffer mounted within each series of plates, and laterally arranged lugs on the 100 105

plates to prevent axial movement of the buffers.

6. A wheel of the character described comprising an inner rim having outwardly projecting lateral flanges, a rim surrounding the latter having inwardly projecting lateral flanges, a plurality of spacing devices interposed between the rims and flanges, each device comprising an endless series of flat plates, pins pivotally connecting the plates together, pins pivotally connecting the plates to the flanges, a yielding cylindrical

buffer mounted within each series of plates, and lateral lugs on the plates engaging the ends of the buffers.

7. A rim spacer for resilient wheels, comprising a polygonal articulated frame, and a resilient core mounted within the latter.

In testimony whereof I affix my signature in presence of two witnesses.

LEO CARLBERGER.

Witnesses:

CARL LOUDENBURG,
CARL LITBEKEK.
